UNITED STATES PATENT OFFICE.

JAMES BRUSH ANDERSON, OF PORTLAND, OREGON.

RAIL-JOINT SHOE AND CLAMP.

SPECIFICATION forming part of Letters Patent No. 777,365, dated December 13, 1904.

Application filed February 15, 1904. Serial No. 193,583. (No model.)

To all whom it may concern:

Be it known that I, JAMES BRUSH ANDERSON, a citizen of the United States, and a resident of Portland, in the county of Multnomah 5 and State of Oregon, have invented a new and Improved Rail-Joint Shoe and Clamp, of which the following is a full, clear, and exact description.

This invention relates to means for reliably 10 supporting and securing in place on cross-ties of a railroad track-rails at their joints, so as to permit expansion and contraction of the track-rails and prevent the track from spreading apart at any point along the line of road.

15 The object of the invention is to provide novel details of construction for a rail-joint shoe that adapt it to serve as a clamp for holding two track-rails at their joint secured together in alinement and afford effective means for retaining the shoe and clamped rails at a desired point on the cross-ties of a railroad.

20 The invention consists in the novel construction and combination of parts, as is hereinafter described and claimed.

25 Reference is to be had to the accompanying drawings, forming a part of this specification, in which similar characters of reference indicate corresponding parts in all the figures.

Figure 1 is a perspective view of the invention 30 applied upon two track-rails at their joint and upon a cross-tie whereon the device is seated. Fig. 2 is a partly-sectional plan view of the improved shoe and clamp, showing the two clamping-sections thereof nearly joined together. Fig. 3 is a substantially similar 35 view to Fig. 2, the plane of section being essentially indicated by the line 3-3 in Fig. 6, the twin sections of the shoe and clamp being shown as completely joined together in their bottom portions. Fig. 4 is plan view of the improved rail shoe and clamp. Fig. 5 is a reversed plan view of the same, showing the 40 formation of the lower side of the device; and Fig. 6 is a transverse sectional view of a track-rail and an end view of the improved shoe and clamp secured thereto.

45 As the improvement is particularly available as a clamping-support for the meeting ends of two similar track-rails, the device complete is afforded such length as will adapt it

to receive and properly embrace the end portions of two track-rails at their joint, as indicated in Fig. 1, these rails being of the usual I form in cross-section, each having a ball A, web A', and base-flange A².

55 The improved rail-joint clamp consists of two similar sections, each section comprising one side and a half of the bottom wall therefor. The side portion of each shoe-section is so shaped that it provides an upright wall 10, which in service has contact with the alined sides of the webs of two track-rails at and near their joint a. Integral with the wall 10, that serves as a fish-plate, a cap-plate 11 is formed, which projects laterally from the 60 lower edge of the upright wall 10 and may incline slightly downward, so as to have contact with the upper surface of a base-flange A². Each cap-plate 11 is return-bent at b, forming an acute-angular corner adapted to receive 65 and incase the free side edge of a respective base-flange A² when the shoe-sections are mounted upon the track-rails for service.

70 The bottom wall of each half-section of the improved shoe and clamp extends from a respective corner b, and said bottom portions are level one with the other on their upper surfaces. At and near opposite ends the bottom walls of the shoe-sections are formed of 75 a width nearly equal to that of the complete shoe when its sections are joined together, the width of these similar end portions 12 of the two bottom sections being respectively defined by a straight edge c, that has contact with a like straight edge c' on a corresponding 80 narrow bottom portion 12^a, which at a respective end thereof is a completing portion of the two-part bottom wall. On each bottom portion 12 and extending from the inner termination c² of each straight edge c an acute- 85 angular tongue 12^b is formed. The width of each tongue 12^b at its base is defined by a slightly-concave corner d and the inner end c² of a respective straight edge c. Between an inner termination c³ of the straight edge c', which 90 defines the length of a respective narrow bottom portion 12^a and a rounded corner e, that is spaced therefrom a distance about equal to the width of each tongue 12^b at its base, a V-shaped notch g is formed in the offset afforded 95 100

by the junction of a bottom portion 12^c, that extends between the narrow bottom portion 12^a at one end of a bottom wall for a half-section of a shoe and the wide bottom portion 12^b at the opposite end thereof. Between the corners *e* and *d* on each bottom half-section a straight edge *h* is formed, these straight edges that are parallel with the angular corners *b* defining the width of a respective middle bottom portion 12^c. It will be seen that if the two half-sections of the shoe and clamp are caused to interengage longitudinally the tongues 12^b will enter the notches *g* and fully occupy them when the straight edges *h* have contact with each other, and this contact of the tongues and notches at their edges will draw the two half-sections of the shoe and clamp toward each other as the sections are forced together endwise, so as to clamp them upon the webs and base-flanges of two track-rails at and near the joint between ends of said rails.

The side walls 10 are thickened toward their centers by the curvature of their outer sides, as indicated at *i*, and it will be seen that this increase in thickness greatly strengthens the side walls of the shoe opposite the joint between two rail ends that are clamped by said side walls. It will furthermore be seen that the material at the corner *b*, where the cap-plate 11 on each shoe-section merges into the bottom plate thereon, is thickened by convexly curving the outer surface of the corner, as at *b'* in Fig. 5, this increase in thickness adding materially to the strength of a respective half-section of the improved shoe.

There is a series of spaced **V**-shaped stiffening-ribs 13 formed on the bottom wall of the two-part shoe, these ribs extending longitudinally throughout the length thereof and serve to reinforce the tongues 12^b, upon which two of said ribs are formed.

In each of the corners *b* at suitable points two notches *m* are formed for reception of the bodies of railroad-spikes. In the side walls 10, that are oppositely disposed for embrace of the webs *A'* on track-rails that are to be clamped together in sequence and seated upon one or more cross-ties *B*, a plurality of transverse perforations *n* are formed for reception of clamping-bolts 14, that are provided with nuts 15, as indicated in Fig. 1. It will be evi-

dent that when the bolts, such as 14, are inserted in all the perforations *n* (four being shown) and the nuts 15 screwed thereon, so as to draw upon the bolts, that are of course provided with heads 14^a, the two sections of the improved shoe will be forcibly clamped upon the rail-webs, and the base-flanges of the track-rails will at the same time be clamped by engagement of the inner surfaces of the corners *b* therewith.

In application assuming that the two-part shoe has been clamped upon two track-rails at their meeting ends and the shoe seated upon a cross-tie *B*, the act of driving spikes into the cross-tie and in engagement with a respective notch *m* will embed the ribs 13 into the cross-tie and hold the track-rails immovable.

Having thus described my invention, I claim as new and desire to secure by Letters Patent—

1. A track-rail shoe and clamp, comprising a two-part shoe having a two-part bottom wall, **V**-shaped tongue and notched connection between the opposed edges of the bottom-wall sections, said shoe being adapted to clamp upon the webs and base-flanges of two alined track-rails, the top face of the bottom wall of the shoe being flat and adapted to meet in flat engagement with the bottom faces of the meeting rails, **V**-shaped ribs spaced apart on the under side of the shoe-bottom, said ribs having sharpened lower edges adapted to be driven into the cross-ties when the rails are spiked down, the sides of the shoe and the webs of the meeting rails having registering openings, and bolts and nuts engaging said openings for holding the shoe clamped upon the rails.

2. A track-rail shoe and clamp, comprising a two-part shoe having a two-part bottom wall, interlocking connections for the two parts of the bottom wall, and sharp **V**-shaped, longitudinally-extending ribs on the bottom of the shoe, said ribs being adapted to be driven into the cross-ties when the rails are spiked down.

In testimony whereof I have signed my name to this specification in the presence of two subscribing witnesses.

JAMES BRUSH ANDERSON.
